In Germany September 26, 1936

12 Claims. (CL 177—380)

This application is an improvement upon the impulse sender disclosed in my prior United States Patent No. 2,251,666, issued January 24, 1941, which relates to a registering device in which condensers are employed as registering elements and are variously charged in accordance with the switching operation to be registered. The discharge current from the registering condensers controls the switching operations which are to become effective at a given time. In the case of the embodiment described in the prior application the switching operations to be performed consist of a numerical selection for setting telephone switches. In order to be able to determine the number of impulses to be transmitted by means of the discharge current from the registering condenser a relay is provided which remains energized for a duration determined by the strength of the discharge current and thus determines the number of impulses to be transmitted. The present invention avoids this sensitive relay which is apt to prejudice the efficiency of the system. The present invention makes a further improvement upon the arrangement according to the prior application in that for determining the charge on the registering condenser which is characteristic of the switching operation to be performed, it is not the charge contained in but the potential across the condenser which is decisive. This means that the value of the capacity of the individual registering condenser can deviate from the nominal value without endangering the efficient operation of the register. This advantage is obtained by the invention in that for carrying out the switching operation registered by the state of charge of the registering condensers an opposing potential is applied which compensates the potential of the condensers, the required switching operation (the controlling of an impulse sender) being controlled by means of a device for determining the value of the potential at the registering condensers. This opposing potential according to the invention is applied in stages to the condenser and the impulse sender is caused to transmit one impulse at each stage. As soon as the opposing potential corresponding to the completely discharged state of the register condenser is reached, the device for determining the value of the potential of the registering condenser becomes operative and prevents the impulse sender from transmitting further impulses.

The invention contemplates two embodiments for the step-by-step connection of the opposing

potential and these are represented in Figs. 1 and 2.

Fig. 1 represents a circuit in which the opposing potential is applied in stages by a stepping switch and Fig. 2 represents a circuit in which the step-by-step application of the opposing potential is effected by means of an auxiliary condenser which is discharged in stages by a second condenser.

Fig. 1 represents a numerical sender for telephone systems having a single set of keys common to a number of selecting stages. The keys T₁ to T₁₀ are connected to individual tappings from a potential divider which is formed by the resistances W₁₁ to W₁₀. The numerals 6, 12, 18, etc., indicate the voltages which may be obtained at the respective points on the voltage divider. As in the case of the prior application, on depressing one of the keys T₁ to T₁₀ the contact 10 TT is simultaneously closed. Relay X draws up in the following circuit: earth—4u—TT—1y—X—battery. Assuming that key T₃ has been depressed, a condenser C₁, C₂, etc., is charged in accordance with the potential from the potential divider corresponding to the key T₃. Since the potential is divided into 10 stages by the resistances W₁₁ to W₁₀ which may be equal to one another the key T₃ is connected to a potential of 18 volts above earth potential. The registering condenser C₁ is charged in the following circuit: battery, 6x, T₃, 2y, 3u, S₁, bank contact O, C₁, 2u, earth. Relay Y energizes over contact 1x, and at contact 2y breaks the charging circuit of the registering condenser. At contact 1x, relay Z was energized, and this at contact 3z operates the rotary magnet DS of the stepping switch S as soon as relay X has been deenergized by contact 1y. The rotary magnet DS steps the wipers S₁ to S₁₀ one step so that the second registering condenser C₂ is set in readiness to register a second digit over wiper S₁. The switching operations which have been described are repeated until the condensers C₁ to C₆ are charged in accordance with the keys T₁ to T₁₀ which have been depressed. As soon as the stepping switch S has reached contact 6, relay U operates over: earth, S₁₀, U, battery. The energizing of relay U is the signal that the registered impulses are to be transmitted in succession. Through the depression of the key T₃ the condenser C₁ was charged at a potential of 18 volts. As soon as relay U operates, the condenser C₁ is connected over contacts 2u and 3u and contact 6 of wiper S₁ in series with the 55 volt battery over wiper M₁ on bank contact O.

The condenser C_1 operates as a battery of 18 volts potential. Accordingly, it applies to the grid of the tube R a potential of $60+18=78$ volts as against the 60 volts applied to the cathode of the tube, i. e., the grid is given a negative bias of $78-60=18$ volts relative to the cathode. This negative bias on the grid blocks the anode current so that relay H cannot energize. Over contact $1u$, relay A operates in the following circuit: earth, wiper MII on contact O , $1u$, $3k$, $1b$, A and battery. The first impulse is transmitted at contact $2a$. Contact $1a$ switches on relay B , which breaks the energizing circuit for relay A at contact $1b$. Relays A and B operate together as an automatic interrupter. The resistances connected in multiple with the windings of relays A and B , make these relays somewhat slow to release after their circuits are opened. Each time relay B energizes, the rotary magnet DM of the stepping switch M is energized over contact $2b$ so that the wipers MI and MII are advanced step-by-step on the energization of magnet DM . When wiper MI comes to the next contact the value of the potential on the grid of the tube is altered. The bank contact O of wiper MI is connected to the 60 volt tapping. The bank contact 1 is connected to the 54 volt tapping and the bank contact 2 to the 48 volt tapping and so on. When wiper MI rests on the contact 2 a potential of $48+18=66$ volts is applied to the grid, i. e., the grid still has a bias of -6 volts relative to the cathode. As soon as the wiper has reached the third contact, the potential of $42+18=60$ volts is applied to the grid, i. e., the grid is no longer biased relative to the cathode voltage of 60 volts. Relay H now operates, since the grid no longer blocks the anode current. During the stepping of the stepping switch M to the third contact, relay A was three times energized so that the depression of the key 3 has resulted in the transmission of three impulses. As soon as relay H draws up, contact $2a$ is rendered inoperative by contact $2h$. Relay K operates over contact $3a$ and locks up over contact $4k$, dependent on relay Z . Relays A and B continue to operate as an automatic interrupter and advance the stepping switch M into the rest position. The interruptions at contact $2a$ however, remain inoperative at this time. By means of contacts $1k$ and $2k$ the resistances connected across the windings of relays A and B are disconnected so that these relays now operate more rapidly than before to cause more rapid rotation of the switch M . As soon as wiper MII has reached the zero position, relay Z operates over its winding ZII in the following circuit: earth, MII , $1u$, $1h$, $1w$, ZII , battery. During the impulsing by relay A , relay V was energized over contacts $3h$ and $5a$. This relay is slow-to-release and at contact $1v$ energizes slow relay W . As soon as relay H energized, the circuit for relay V was broken by contact $3h$ so that relay W released again. The rotary magnet DS was energized over contact $3z$ by the operation of relay Z , and relay K is restored by means of contact $1z$. Wiper SI thereby comes to the next contact, so that now the potential across condenser $C2$ can be transmitted by the step-by-step application of the opposing potential. The switching operations which have been described are repeated.

In order to be able to dial with fewer than six digits a starting key StT is provided. If for example, a two-digit selection is desired the stepping switch S is advanced to the second contact

by the successive depression of two of the keys $T1$ to $T10$. Since the desired switching operations can now take place the stepping switch must be advanced to contact 6 . This is brought about by depressing the starting key StT whereupon relay X operates in the following circuit: earth, $SIII$, bank contacts 1 to 5 , 1 StT , $1y$, X , battery. Over contact $4x$ relays Y and Z are energized so that the rotary magnet DS is energized over contact $3z$ and relays X and Y operate together as an automatic interrupter until the stepping switch S has reached contact 6 . At contact 6 relay U energizes and the operations already described set in and enable the two registered impulse trains to be transmitted. The key AT is a releasing key by means of which digits already registered can be released. Reference may be made to the prior application in which the corresponding switching operations are described.

In the embodiment represented in Fig. 1 the stepping switch M is subjected to hard wear because this stepping switch has to rotate once for every selecting stage. In the embodiment shown in Fig. 2, this stepping switch is replaced by a relay arrangement which is not used to such a great extent, in connection with two auxiliary condensers. The switching devices are otherwise the same as in the embodiment shown in Fig. 1 so that they need not be referred to in detail. It will again be assumed that the registering condenser $C1$ is charged to a potential of 18 volts. The step-by-step application of the opposing potential starts with the operation of relay U as soon as the stepping switch S has reached contact 6 . When the stepping switch S is advanced to contact 6 , the condenser $C1$ has been charged to the full potential of 60 volts over contact $2z$: earth, $C1$, $2z$, battery. Thus the potential on condenser $C1$ is connected over contact $2u$ in series with the 18 volt potential on condenser $C1$ so that the total potential on the grid of the tube amounts to $60+18=78$ volts. Over contact $1u$, relay A is energized in the following circuit: earth, $1u$, $1h$, $1b$, A , battery. Relay B is energized by contact $1a$. Over contacts $3b$ and $2b$ the condenser $C8$ is charged at the full potential of 60 volts. The capacity of condenser $C8$ is considerably less than that of condenser $C1$. The condenser $C8$ is therefore charged in the opposite sense when the condensers $C1$ and $C8$ are connected in series to earth over contact $2b$ and $3b$. When relay B energizes the charge on condenser $C1$ is accordingly reduced by an amount corresponding to the charge on condenser $C8$. The charge on condenser $C1$ is then diminished a further amount which corresponds to the charge now imparted by condenser $C1$ to condenser $C8$ in accordance with the potential still obtaining on condenser $C1$. The dimensions of the condensers $C1$ and $C8$ are so chosen that the reduction of the potential on condenser $C1$ by the step-by-step discharge over condenser $C8$ takes place in convenient stages as regards potential. In the example given the potential of 18 volts on the registering condenser $C1$ is to be compensated by connecting the condenser $C8$ to the condenser $C1$ three times. As soon as condenser $C1$ possesses the opposing potential corresponding to that of the registering condenser, relay H pulls up so that relay Z energizes over contact $1h$ and the impulse sending relay A is brought to rest. Relay Z over contact $3z$ operates the rotary magnet DS and thereby causes wiper SI to be advanced to the next contact. The

digit registered by the next register condenser can now be transmitted by determining the potential on this condenser.

What is claimed is:

1. In an impulse sender for registering a digit as a quantity of charge on a condenser and subsequently retransmitting the digit as one or more impulses, a plurality of sources of potential, each source differing from the other sources in the value of its potential, means for successively connecting said sources of potential in series with said condenser during the transmission of the impulses, and means operated to terminate the transmission of the impulses when the combined voltages of said condenser and of that one of said sources connected in series therewith equals a predetermined value. 5
2. In an impulse sender in which a digit is registered as a quantity of charge on a condenser, means for connecting a source of voltage in series with the charged condenser and for progressively reducing the voltage of said source, means for producing and transmitting an impulse each time said voltage source is reduced in value, and means controlled conjointly by the condenser and said first means to terminate the transmission of said impulses when the voltage of said charged condenser plus the voltage of said source reaches a predetermined value. 10
3. In combination, a condenser, means for charging said condenser to a predetermined potential, a source of potential, means for connecting said potential source in series with said charged condenser, means for reducing the potential of said source in substantially uniform steps, and means operated responsive to the sum of the potential of said charged condenser and said source of potential reaching a predetermined value. 15
4. In combination, a first condenser, means for charging said first condenser to any one of a plurality of predetermined potentials, a second condenser, means for charging said second condenser, a third condenser, means for intermittently connecting said third condenser with said second condenser to reduce the charge on said second condenser in substantially uniform steps, means for connecting said second condenser in series with said first condenser, and means controlled by said first and second condensers operated when the sum of their potentials reaches a predetermined value. 20
5. In combination with a grid controlled space discharge device; means for controlling the potential of the grid, comprising, a first condenser; means for charging said first condenser to a predetermined value; a second condenser; means for charging said second condenser; means for connecting said condensers in series to said grid, thereby to establish on said grid a potential dependent upon the algebraic sum of the charges on said two condensers; a third condenser; and means for altering the potential on said grid by charging said third condenser in a direction opposite to the charge contained in the second condenser, connecting said second and third condensers in series to partly discharge said second condenser, and disconnecting said third condenser from said second condenser. 25
6. In combination; a first condenser; means for charging said first condenser to any one of a plurality of different values; a second condenser; means for charging said second condenser; a third condenser; means for charging said third condenser in a direction opposite to 30
7. In combination; a first condenser; means for charging said first condenser to a predetermined value; a second condenser; means for charging said second condenser; means for connecting said condensers in series; a third condenser; means for charging said third condenser in a direction opposite to the charge contained in the second condenser, for connecting said second and third condensers in series to remove a portion of the charge from said second condenser, and for disconnecting said third condenser from said second condenser, said last-named means being repeatedly operable to reduce the charge on said second condenser in substantially uniform steps; and means under the joint control of said first condenser and said second condenser operated responsive to the charge on said second condenser reaching a value which bears a predetermined relationship to the value of said charge on said first condenser. 35
8. In combination, a plurality of sources of potential varying in value from each other in substantially uniform steps, a condenser, means for charging said condenser from one of said sources, a potential responsive device, means for connecting said charged condenser to said potential responsive device and for connecting said condenser successively to each of said sources, said device operating when the sum of the potentials thus obtained reaches a predetermined value. 40
9. In an impulse sender for registering a digit as quantity of charge on a condenser and subsequently retransmitting the digit as one or more impulses; means for successively connecting a plurality of different potentials of diminishing values in series with said condenser to successively reduce the effective total potential in substantially uniform steps, the number of steps required to reduce said effective total potential to a predetermined value being thus a measure of the charge on the condenser and hence characteristic of the digit registered. 45
10. In combination, a condenser, means for charging said condenser to any of a plurality of different potentials, a space discharge device having a grid, means for completing a biasing circuit to said grid, said circuit including said charged condenser and, in series with said condenser, an auxiliary potential, said condenser and said auxiliary potential so poled in said circuit that each tends to bias said grid negatively, whereby said condenser and said auxiliary potential together raise the total negative potential of said grid to a value above that at which said device will discharge, means for thereafter reducing said auxiliary potential in substantially uniform steps without altering the charge on said condenser, thereby to correspondingly reduce the potential of said grid, and a discharge circuit for said device energized responsive to the potential of said grid reaching the value at which said device discharges. 50
11. In combination, a source of direct current, 75 a voltage divider shunting said source, a con-

denser, means for connecting said condenser across different portions of said voltage divider at different times, thereby to charge said condenser at each of said times in accordance with the voltage drop in the portion across which said condenser is connected, means operated each time said condenser has been thus charged for thereafter connecting said condenser successively to different portions of said voltage divider without altering the original charge on said condenser, and means for testing the effective total potential of said charged condenser and each said portion of said voltage divider as the condenser is connected to that portion.

12. In combination, a condenser, a source of 15

5 direct current voltage, means for connecting said condenser to said source to charge the condenser, means operated after said condenser has been charged for connecting the charged condenser and said source in series so that the effective total potential of said condenser and said source together is greater than the potential of either said condenser or said source alone, means for then gradually reducing the voltage of said source without altering the charge on said condenser, 10 and a device operated responsive to said effective total potential of said condenser and said source reaching a predetermined value.

HINRICH DÖHLE.
